(57) **CLAIM**

The ornamental design for an illuminated paddle, as shown and described.

DESCRIPTION

FIG. 1 is a front perspective view of an illuminated paddle illustrating our new design;

FIG. 2 is a back view of the design of FIG. 1;

FIG. 3 is a front view of the design of FIG. 1;

FIG. 4 is a side view of the design of FIG. 1;

FIG. 5 is a side view of the design of FIG. 1;

FIG. 6 is a top view of the design of FIG. 1;

FIG. 7 is a bottom view of the design of FIG. 1; and,

FIG. 8 is a front perspective view of the design of FIG. 1 in an illuminated state.

The broken lines represent portions of the structure and the environment that form no part of the claimed design. The dash-dot-dash lines radiating from the illuminated paddle in FIG. 8 indicate illumination only and form no part of the claimed design.
